UNITED STATES PATENT OFFICE.

SIMON LIEBERMAN, OF NEW YORK, N. Y.

PLATFORM FOR STAIRWAYS.

1,248,141.

Specification of Letters Patent. Patented Nov. 27, 1917.

Application filed January 20, 1917. Serial No. 143,451.

To all whom it may concern:

Be it known that I, SIMON LIEBERMAN, a citizen of the United States, and a resident of the city of New York, borough of 5 Manhattan, in the county and State of New York, have invented a new and Improved Platform for Stairways, of which the following is a full, clear, and exact description.

10 The invention relates to metallic building structures, and its object is to provide a new and improved platform for stairways arranged to dispense with supporting T-irons and sockets therefor, and to permit of economically manufacturing and setting up the 15 platform and at the same time providing a trussed platform which is exceedingly strong and durable.

In order to accomplish the desired result, 20 use is made of a metal platform provided with a plate of sheet steel or other sheet metal, and having depending integral ribs formed by doubling up some of the platform material during the process of manufacturing 25 the platform plate, the side members of the doubled-up ribs being spaced apart to provide trusses for reinforcing the platform plate and to provide pockets for the reception of some of the cementitious material 30 used as a covering for the platform.

A practical embodiment of the invention is represented in the accompanying drawings forming a part of this specification in which similar characters of reference indicate corresponding parts in all the views.

Figure 1 is a sectional side elevation of the platform as applied to a stairway, the section being on the line 1—1 of Fig. 2;

Fig. 2 is a plan view of the same with the 40 platform covering removed and the stair string and the walls of the building shown in section;

Fig. 3 is a longitudinal section of the same on the line 3—3 of Fig. 2;

Fig. 4 is an enlarged longitudinal section of a portion of the platform;

Fig. 5 is a sectional perspective view of a portion of one of the supporting bars of the supporting frame for the platform plate;

50 and

Fig. 6 is a sectional perspective view of a portion of the platform plate.

In the manufacture of platforms for iron stairways, it has heretofore been customary 55 to use a frame supporting a flat metallic plate along the margin thereof, the platform

plate being supported intermediate its ends by transverse T-irons fitting at their ends into sockets, bolted, riveted or otherwise fastened to the side members of the supporting frame. This construction involved considerable expense, material, and labor, and in my invention, presently described in detail, I entirely dispense with the T-irons and the sockets, and at the same time provide a 60 65 trussed platform which is exceedingly strong and durable.

The platform of the iron staircase, shown in Figs. 1, 2 and 3, consists essentially of a platform plate 10 resting along its margin 70 on a supporting frame formed of angle iron end bars 11 and 12, an angle iron rear bar 13 and a front channel bar 14. The supporting frame described is attached to the stair string 15 by the use of rivets, bolts or similar fastening devices 16.

The platform plate 10 is preferably made of sheet steel or similar sheet material and is provided with depending, transversely extending ribs 20 struck up from the sheet 80 material by doubling portions thereof, the side members of each doubled portion being spaced apart, as plainly shown in Figs. 3 and 4, to provide a strong reinforcing truss member and at the same time to provide a 85 pocket which is open at the top. The top member of the bar 13 of the supporting frame is provided with spaced notches 25 into which extend the rear ends of the ribs 20, the front ends of which are cut off and 90 a portion of each rib is slotted to fit the top member of the bar 14 (see Figs. 1 and 6).

In assembling the parts for the platform the supporting frame is first attached to the stair string 15 and then the platform plate 95 10 is placed in position on the supporting frame and fastened to the top members thereof by suitable bolts 26 or other suitable fastening devices. The platform plate is then provided with a covering which 100 may be in the form of a slate slab or in the form of a plastic cementitious material 30, a portion of which passes into the pockets formed by the ribs 20 so as to anchor the cementitious covering material in place on 105 top of the platform plate 10.

In case the covering of the platform is of a cementitious material 30 as above described and illustrated in the drawings, then use is preferably made of reinforcing rods 110 40 each embedded in the material 30 contained in the corresponding pocket formed

by each rib 20. The ends of each rod 40 are held in apertures formed in the front and rear supporting bars 13 and 14 of the supporting frame and the middle portion of each rod 40 is supported by a wire 41 passing around the rod and resting with its ends on the upper surface of the platform plate 10, as plainly shown in Figs. 2 and 4. It is understood that the rod 40 and its supporting wire are placed in position prior to placing the cementitious material 30 in position and the said rod and wires are embedded subsequently in the cementitious material to reinforce the same and thus greatly strengthen the platform.

From the foregoing it will be seen that by the arrangement described the platform plate 10 is strongly reinforced by the use of the integral ribs 20, and the platform parts can be readily and quickly assembled thus dispensing with a considerable amount of labor.

Having thus described my invention, I claim as new and desire to secure by Letters Patent:

1. A platform for metallic stairways, comprising a supporting frame having front and rear supporting bars provided with top members having spaced open ended slots, and a platform plate made of sheet metal

and resting on the said frame, the said platform plate being provided with integral transversely extending vertical depending ribs fitting at their ends into the said slots, concrete reinforcing elements held in the channels of said ribs, and fastening means fastening the platform plate at its margin to the said supporting frame.

2. A platform for metallic stairways having a cementitious covering, comprising a supporting frame having front and rear supporting bars provided with top members having spaced open ended slots, and a platform plate made of sheet metal and resting on the said frame, the said platform plate being provided with integral transversely extending depending ribs fitting at their ends into the said slots, the said ribs formed of doubled portions of the material of the plate, the side members of the doubled portions spaced apart to form channels open at the top of the plate, reinforcing rods suspended within said channels, and other reinforcing elements suspending said rods and supported on the upper face of the plate at each side of the channels, and fastening means securing the platform plate at its margin to the said supporting frame.

SIMON LIEBERMAN.
